Primary Examiner — Steven J Czyz*Assistant Examiner* — Hillary Catherine Shepard(74) *Attorney, Agent, or Firm* — Eric Hanscom(57) **CLAIM**

The ornamental design for an office shell, as shown and described.

DESCRIPTION

FIG. 1 is a top perspective view of an office shell showing my new design in an open state;

FIG. 2 is a top perspective view of an office shell shown in a closed state;

FIG. 3 is a front perspective view of an office shell shown in an open state; and,

FIG. 4 is a top perspective view of an office shell shown in a closed state.

The broken lines depict portions of the article that form no part of the claimed design.

1 Claim, 4 Drawing Sheets(56)
